CLAIM

I claim the ornamental design for an adult toy, as shown and described.

DESCRIPTION

FIG. 1 is a front, top, right side perspective view of the adult toy showing my new design;

FIG. 2 is a rear, bottom, left side perspective view thereof;

FIG. 3 is a right side view thereof;

FIG. 4 is a left side view thereof;

FIG. 5 is a top plan view thereof;

FIG. 6 is a bottom plan view thereof;

FIG. 7 is a front view thereof;

FIG. 8 is a rear view thereof;

FIG. 9 is a front, top, right side perspective view of the adult toy with the two end caps removed;

FIG. 10 is a rear, bottom, left side perspective view thereof;

FIG. 11 is a right side view thereof;

FIG. 12 is a left side view thereof;

FIG. 13 is a top plan view thereof;

FIG. 14 is a bottom plan view thereof;

FIG. 15 is a front view thereof;

FIG. 16 is a rear view thereof; and,

FIG. 17 is a cross-sectional view taken along line A--A shown in FIG. 15.

The shading lines shown in the drawings represent the approximate three-dimensional contour of the design, and are not intended to indicate surface decoration.

The broken lines indicate portions of the adult toy that form no part of the claimed design.
